UNITED STATES PATENT OFFICE.

WILLIAM BELL WHITE, OF COLNE, ENGLAND.

OVEN, BOILER, RADIATOR, AND THE LIKE.

1,288,332.

Specification of Letters Patent. Patented Dec. 17, 1918.

Application filed October 13, 1917. Serial No. 196,424.

To all whom it may concern:

Be it known that I, WILLIAM BELL WHITE, a subject of the King of Great Britain, residing at 16 Haverholt, Colne, in the county 5 of Lancaster, England, have invented certain new and useful Improvements in Ovens, Boilers, Radiators, and the like, of which the following is a specification.

This invention relates to ovens and other 10 similar heating or drying devices; and it consists in the novel construction and combination of the parts hereinafter fully described and claimed. In the drawings, Figure 1 is a perspective view of one unit used 15 in constructing an oven according to this invention. Fig. 2 is a front view of a complete oven. Fig. 3 is a perspective view of one oven unit, but shows a modification.

The oven is formed of a series of oven 20 units arranged one above another. The units between the top and bottom units are preferably all alike, and are constructed as shown in Fig. 1. Each unit has a front wall 1, a back wall 2, and side walls 3 and 25 4. The top of the oven unit is a flat plate 5, and its bottom is a similar flat plate. The side walls 3 and 4 have flue openings 6 and 7, and the front wall 1 has a sliding door 8 or other suitable means for cleaning out the 30 soot which accumulates inside the flue chamber formed between the walls of the unit. The side portions 3 and 4 project above the top 5, and the back wall 2 also preferably projects above the top 5, but this is not essential in carrying out the invention.

The projecting side portions of the walls 2 and 4 support the flue chamber or unit next above in the series, and a heating chamber or oven is thereby formed between the two 40 flue chambers.

Each oven or oven chamber *b, d, f*, has an opening or door which communicates with the atmosphere, so that articles may be placed in it to be cooked, heated or dried. A 45 fire-box 10 of any approved construction is arranged under the bottom unit, and has an outlet 11 for the heated products of combustion, which communicates with a similar opening in the bottom of the flue chamber 50 *a* of the lowest unit. A tile or thick metallic plate 10 is arranged at the top of the fire-box under the bottom unit. The superposed flue chambers *a, d, f*, are connected together by flues 12, which are preferably channel- 55 shaped in cross-section, and which have

openings 6^a and 6^c at their end portions. These openings are secured over the openings in the flue chambers, as shown in Fig. 2. The flues 12 are arranged alternately on opposite sides of the units, the lowest flue connecting the openings 6 of the flue chambers *a* and *c*, and the flue 12 next above in the series connecting the openings 7 of the flue chambers *c* and *e*, and so on in the series, so that the heated products of combustion take 60 the course of the arrows shown in Fig. 2.

The flue chamber 13 of the top unit is provided with a suitable chimney 14. The form of the flues 12 may be variously modified in carrying out this invention, and the 65 openings 6 and 7 may be located in various positions in the walls of the flue chambers, as they are not necessarily placed midway between the back and front as shown.

In the modification shown in Fig. 3, the 70 flue inlet 7 and the flue outlet 6 are arranged out of line with each other, and baffle plates or partitions 15 are provided in the flue chamber, to form a tortuous passage in it for 75 the products of combustion, in order that 80 the ovens or heating chambers may be heated more effectively.

I claim as my invention:—

1. A heater constructed of a series of superposed units, each unit being formed separately and the units intermediate of the top and bottom units being similar to each other, each intermediate unit comprising a rectangular flue chamber having side portions which project above its top and which 85 support the flue chamber next above it, an oven being formed by the said side portions between the two flue chambers, each said oven having a separate door opening communicating with the atmosphere, each said 90 flue chamber having also an inlet opening and an outlet opening, and connecting flues secured to the said flue chambers and connecting the outlet opening of each flue chamber with the inlet opening of the flue chamber 95 next above it.

2. A heater constructed of a series of superposed units, each unit being formed separately and the units intermediate of the top and bottom units being similar to each 100 other, each intermediate unit comprising a flue chamber having side portions which project above its top and which support the flue chamber next above it, an oven being formed by the said side portions between the two flue 105 110

chambers and having a door opening which communicates with the atmosphere, each said flue chamber having also an inlet opening and an outlet opening and having also baffle 5 plates which form a tortuous passage in it between its said openings, and connecting flues secured to the said flue chambers and connecting the outlet opening of each flue

chamber with the inlet opening of the flue chamber next above it. 10

In testimony whereof I affix my signature in the presence of two witnesses.

WILLIAM BELL WHITE.

Witnesses:

H. B. CREEKE,
ELSIE L. SPELLMAN.
